METHOD OF PRODUCING TOILET SOAP

John Karl Oskar Hubert Holmberg,
Stockholm, Sweden.Application December 6, 1946, Serial No. 714,533
In Sweden December 19, 1945

5. Claims. (Cl. 260—417)

1

This invention relates to a new and useful method in the saponification of fatty acid esters for the production of milled toilet soaps.

Such soaps have hitherto been produced by saponifying glycerides of fatty acids by means of caustic alkali dissolved in water or alcohol. Generally the saponification is carried out in open vessels, for which reason the reaction temperature must be kept below 100° C., so that the water is not boiled off. After the saponification the soap is salted out, washed for removing the salt and is finally dried to such a moisture content that it becomes malleable. It is evident that the process could be made less expensive, if the salting out and drying operations could be eliminated. For this purpose it has been suggested to undertake the saponification under such conditions that the soap obtained is completely dry and thus will have to be diluted with water before the milling operation. A process of this kind is claimed in the U. S. Patent No. 2,084,446, granted to Henry W. F. Lorenz.

According to Lorenz the saponification of glycerides or other esters of fatty acids is carried out at a temperature above the melting point of the resulting anhydrous soap and in an atmosphere free of air while intimately contacting the mixture with a stream of superheated water vapour. The high saponification temperature according to Lorenz brings about the disadvantage of higher costs and the risk of local super-heatings, resulting in damages of the product. The blowing of steam through the mass always causes a loss of fatty materials distillable with water vapor and thus a decrease in the yield of soap. Finally the soap mass obtained afterwards must be diluted with water before the mass can be milled to toilet soap, this mixing, as is well known, being a rather serious operation.

The present invention consists in a new method for the saponification, resulting in a soap mass of a consistency which makes it directly malleable for the production of toilet soaps. As starting material for the process of the invention I use certain alcoholic esters of fatty acids, namely such esters of which the alcohols have a lower boiling point than water under the saponification conditions. Such esters according to my invention are saponified with alkali, preferably caustic alkali in the presence of a diluent such as water or alcohol or a mixture of water and alcohol in such a quantity that the diluent remaining after saponification will suffice for making the soap mass malleable, the saponification being carried

2

out at a temperature suitably below 125° C., at which the charge is semiliquid to liquid.

As has been stated above the alcohols of the esters used as starting material must be of the type having a lower boiling point than water at the prevailing saponification conditions. Such alcohols are for instance methanol, ethanol and propanol, of which the methanol esters are preferred due to the simpler and cheaper methods of recovering this alcohol. As has been stated above the reaction is to be carried out at so high a temperature that the mass is liquid. Further, the temperature must be above the boiling point of the alcohol of the ester. By using such temperature the alcohol liberated during the saponification is boiled off and may be recovered by known methods.

According to a preferred embodiment the saponification is carried out in a still pot, provided with stirring means and a fractionating column. By constructing the fractionating column with a sufficient number of plates and by using a suitable reflux ratio it is possible to obtain a substantially concentrated alcohol and simultaneously to maintain such a water content in the pot that the resulting soap is directly malleable. However, if the soap is to be completely freed from any traces of the alcohol one cannot prevent part of the water of the order of a few per cent being simultaneously distilled off. If desired the correct water content of the mass could be adjusted by addition of water towards the end of the saponification process.

The caustic alkali used for the saponification could be added either at once from the beginning or in portions during the process. It is also possible to add the alkali in solid form or as a concentrated solution, the water content of which possibly together with otherwise added water must not decrease the quantity of water required for making the soap malleable.

In the following the process of the invention will be more fully described in an example using methyl esters of fatty acids as starting material and with reference to the accompanying drawings, in which

Fig. 1 shows more or less diagrammatically a soap pan of the type hitherto used but fitted with a cooler for the recover of alcohol; and

Fig. 2 shows an improved apparatus in which the saponification vessel consists of a still pot provided with a fractionating column.

In the drawings, reference number 1 refers to a saponification vessel provided with a heating jacket 2 and suitable stirring means 3. Feeding

openings 4 and a discharge 5 for the vapours developed are arranged in the cover 6 of the saponification vessel. The methyl esters and the alkali are introduced into the reaction vessel 1 where they are intimately mixed while being heated. When the saponification reaction has started the heating is gently continued and simultaneously small quantities of water are added in order to maintain the liquid consistency of the soap mass. When the saponification is finished the remaining liberated methanol is driven off preferably while evacuating the reaction vessel. If esters of higher boiling alcohols are used as starting material it is often suitable to carry through the whole saponification reaction below atmospheric pressure for the purpose of maintaining the reaction temperature at reasonable values. Conversely in some cases it is advisable to carry out the reaction at a pressure above atmospheric in order to accelerate the reaction or improve the yield. When the saponification is completed the excess alkali may be neutralized by the addition of free fatty acids.

According to the improved embodiment of the invention illustrated by the apparatus of Fig. 2 the introduction of the starting materials is carried out as described above. During the reaction vapours of water and alcohol, for instance methanol, are evolved, passing through the discharge pipe 5 into a fractionating column 1, from which the reflux is returned to the reaction vessel 1 through a pipe 8. The fractionating column is further provided with coolers 9 and reflux dividers 10, known per se, from which the concentrated alcohol is discharged.

Example.—The apparatus is charged with 1000 kg. methyl ester of palm oil fatty acids (saponification No. 215). The esters are heated to 100° C. and about half of the required alkali, viz. 75 kg. caustic soda in anhydrous form is added while vigorously stirring. The soap formed is dispersed in the molten ester, the charge still being liquid. When the rest of the alkali, 77 kg., is added it is also necessary to add water (totalling 100-200 kg.), and to raise the temperature to about 120-125° C. in order to maintain the liquid condition.

The new saponification method according to the invention makes it possible to produce a toilet soap with a desired free alkali content, very low salt content (originating only from impurities in the caustic alkali used for the saponification), and finally an adjustable water content making the soap readily malleable. Contrary to the previous saponification processes my improved process results in a malleable toilet soap mass in one single step. The alcohol liberated during the saponification can be easily recovered and further it is possible to use the heat of reaction for this latter recovery.

Of course, it is possible according to the invention as well as in methods previously known to add soap previously produced from the beginning or during the process for the purpose of facilitating the emulsification of the molten esters.

Finally, it is also possible to add other chemical compounds known per se as additional substances in soaps, such as over-fattening agents, essences, salts, solvents, alcohols, suitably fatty alcohols and sulphonated fatty alcohols.

I claim:

1. The method of producing a malleable soap directly with the saponification with alkali of fatty acid esters of such alcohols that have a lower

boiling point than water under the saponification conditions employed, which method comprises saponifying such fatty acid esters with alkali in the presence of a liquid diluent for the soap and at a temperature at which the charge is from semi-liquid to liquid above the boiling point of the alcohol liberated from the esters and not in excess of about 125° C., said diluent being volatile under the saponifying conditions and having a boiling point over that of the alcohol liberated from the esters, distilling off the alcohol liberated from the esters, and continuously fractionating the vapors evolved during the saponification as they are evolved to rectify off the alcohol liberated from the starting ester and drawing it off separately while returning the diluent fraction as the reflux to the reaction mass, the diluent having been included in a quantity substantially equal to that desired in the soap produced and adjusted to that concentration so that after the removal of the liberated alcohol, the soap mass on cooling is directly malleable.

2. The method as claimed in claim 1, wherein the diluent is a hydroxyl-group-containing material which is a member of the class consisting of water, ethanol, and a mixture of water and ethanol.

3. The method as claimed in claim 2, wherein the diluent is water and it is added to the reaction mass in such quantity that its content in the soap mass remaining after the saponification is completed is between about ten and about thirty percent.

4. The method as claimed in claim 3, wherein the quantity of water added is such that its content in the soap mass after the saponification is completed is between about ten and about twenty percent.

5. The method of producing a malleable soap directly with the saponification with alkali of the methyl ester of palm oil fatty acids, which method comprises saponifying said fatty acid esters with caustic alkali in the presence of water as a diluent for the soap at a temperature raised to between about 120° and about 125° C., distilling off the methanol liberated from the esters, and continuously fractionating the vapors evolved during the saponification as they are evolved to rectify off the alcohol liberated from the starting ester and drawing it off separately while returning the diluent fraction as the reflux to the reaction mass, the water having been included in a quantity sufficient to give a concentration of between about ten and about twenty percent in the finished soap and adjusting its content during the treatment so that after the methanol is distilled off, the soap mass on cooling contains between about ten and about twenty percent of water and is directly malleable.

JOHN KARL OSKAR HUBERT HOLMBERG.
